(57) **CLAIM**

The ornamental design for a window bird feeder, as shown and described.

DESCRIPTION

FIG. 1 is an elevated perspective view of the feeder with attachment means in phantom;

FIG. 2 is an elevated frontal view thereof with attachment means in phantom;

FIG. 3 is an elevated rear view thereof with attachment means in phantom;

FIG. 4 is a top plan view thereof;

FIG. 5 is a bottom plan view thereof;

FIG. 6 is an elevated left-side view thereof; and,

FIG. 7 is an elevated right-side view thereof, establishing that both sides of said feeder are essentially identical.

The portions rendered in phantom lines are for illustrative purposes only and form no part of the claimed design.
